(57) **CLAIM**

I claim the ornamental design for a beverage container, as shown and described.

DESCRIPTION

FIG. 1 is a front perspective view of a beverage container from a front side showing my new design;

FIG. 2 is a rear perspective view thereof;

FIG. 3 is a top plan view thereof;

FIG. 4 is a bottom plan view thereof;

FIG. 5 is a side view thereof;

FIG. 6 is cross-sectional view thereof taken along the line 6-6 of FIG. 2;

FIG. 7 is a cross-sectional view thereof taken along the line 7-7 of FIG. 2; and,

FIG. 8 is a cross-sectional view thereof taken along the line 8-8 of FIG. 2.

The portions of the drawings shown in broken lines form no part of the claimed design.
